UNITED STATES PATENT OFFICE.

HERBERT C. BLISS, OF ATTLEBORO, MASSACHUSETTS.

DESIGN FOR A LOCKET.

42,454.

Specification for Design.

Patented May 7, 1912.

Application filed February 10, 1912. Serial No. 676,832. Term of patent 7 years.

To all whom it may concern:

Be it known that I, HERBERT C. BLISS, a citizen of the United States of America, residing at Attleboro, in the county of Bristol and State of Massachusetts, have invented a new, original, and ornamental Design for a Locket, of which the following is a specification, reference being had to the accompanying drawings, forming a part thereof, in which—

Figure 1 is a plan or front view of a locket showing my new design; and Fig. 2 is a corresponding edge view of it.

I claim:

The ornamental design for a locket, as shown and described.

HERBERT C. BLISS.

Witnesses:

ERNEST M. BLISS,
M. E. CARPENTER.
